LUMINAIRE

Myron F. Pettengill, Hendersonville, N.C., assignor to
General Electric Company, a corporation of New York

Filed Nov. 24, 1961, Ser. No. 67,669

Term of patent 14 years

(Cl. D48—23)

FIG. 1 is a front elevational view of a luminaire, showing my new design;

FIG. 2 is a side elevational view thereof;

FIG. 3 is a top plan view thereof;

FIG. 4 is a bottom plan view thereof;

FIG. 5 is a front elevational view of a modified form of the luminaire shown in FIG. 1;

FIG. 6 is a side elevational view thereof as shown in FIG. 5;

FIG. 7 is a top plan view thereof as shown in FIG. 5; and

FIG. 8 is a bottom plan view thereof as shown in FIG. 5.

I claim:

The ornamental design for a luminaire, as shown and described.
